UNITED STATES PATENT OFFICE.

FRIDOLIN POLZER, OF NEW YORK, N. Y., ASSIGNOR TO THE E. H. HOTCHKISS COMPANY, OF NORWALK, CONNECTICUT, A CORPORATION OF CONNECTICUT.

STAPLING MACHINE.

Application filed September 11, 1920. Serial No. 409,616.

To all whom it may concern:

Be it known that I, FRIDOLIN POLZER, a citizen of the United States, residing at New York city, in the county of New York and State of New York, have invented a certain new and useful Improvement in Stapling Machines, of which the following is a specification.

My invention relates particularly to a machine adapted to insert staples in thin wood, paper, leather, or any other thin substance or article; but it has relation especially to stapling machines used for fastening together sheets of paper, cloth, or other fabrics.

The object of my invention is to provide a stapling machine of the above kind which shall be very compact, stable, reliable, durable and inexpensive, but which cannot easily become clogged, by any accumulation of bent staples therein, for the reason that bent staples are not likely to be formed by it and for the reason that if any staples should be defective or bent they may be easily released from the machine, which is adapted to be used with either short or long strips of staples. These strips may be introduced or removed at will, it being practicable to remove them either through the feed opening or through an opening opposite thereto, or through either one of a plurality of lateral openings. A further object of my invention is to provide a rugged and simple machine whose parts shall be easy to make and to assemble, which shall be practically "fool-proof", and in which a new strip may be fed even though there remain in the machine only one staple of the previous strip.

The present machine, which is in some respects similar to that described in my application Serial Number 382,575, filed May 19, 1920, has been provided in order to overcome the disadvantages of all previous machines from which the above mentioned functions are absent, or in which they are less perfectly performed.

Further objects of my invention, including certain details which aim to diminish the total height of the machine, to simplify and improve the plunger construction, to provide independent means for depressing the feeding pawl and the back-stop lever, and to obviate an undue weakening or liability to derangement of parts, or to a displace-

ment of staples in the region where the 55 plunger acts thereon to cut them successively from a strip and to drive them home, will appear from the detailed description thereof contained hereinafter.

While my invention is capable of being 60 carried out in many different forms, for the purpose of illustration I have shown only one form of my invention in the accompanying drawings, in which:

Fig. 1 is a vertical section of a machine 65 made in accordance with my invention.

Fig. 2 is a rear view of an advantageous form of plunger for use therein, a preferred form of knob for use at the top of said plunger being shown in section,

Fig. 3 is a bottom view of a part of the new form of main casting, together with associated parts that cooperate in the cutting off of staples, and

Fig. 4 is an elevation of the complete machine.

In the drawings, I have shown a stapling machine comprising a base 1 and a main casting 4. The base preferably has ears 2 to which the main casting 4 is pivoted by 80 means such as a horizontal cutter bar 3, which bar may be secured in the lower part of said casting between spacing plates, such as plates 3^b, by any convenient means such as rivets 5, but preferably in such a way as 85 to leave an inverted U-shaped recess 3^a in the casting 4 and above the bar 3,—through which U-shaped recess a strip of staples 10, may advance, astride of said bar.

In the top of the casting 4, there is shown 90 a recess 5^a, through which extends the composite plunger 6, 6^a, moving substantially at right angles to the bar 3, and having a striking head such as a knob 7, at the top thereof, said knob serving also to confine a 95 coil spring 8 located around the composite or bipartite plunger 6, 6^a, between the surrounding knob 7, (preferably comprising the parts 7^a and 7^b, as shown) and the main casting 4.

In the present embodiment the plunger 6, 6^a, thus comprises two parallel flat elements which are preferably of steel and may be secured together, as by electric welding, near the point of their union, by means such as a projection H, with a counterpart steel element 7^a, which is preferably associated with a covering element, which may be of a

softer and non-corrosive metal material such as aluminum, crimped or otherwise secured thereon.

The shape of the elements 6, 6^a, conforming to that of the channel in which they run, is sufficient to keep these elements together and to prevent the composite plunger 6, 6^a, from turning. As in other machines of this general character, the lower end of the plunger element (but in this case only the plunger element 6) serves as a cutter, therein acting in conjunction with the bevelled forward end 3^c of the bar 3 to sever a staple from the end of a staple strip 10 and to force the same downwardly within slots 11, located in the casting 4, against a recessed abutment 12 adapted to crimp the ends of the staple after it has passed through a fabric or other material or article which may have been inserted between the casting 4 and the abutment 12.

The preferred means for feeding, holding and releasing the strip of staples comprises a feeding pawl 18 and a back-stop lever 23, shown as housed within the mentioned internal recess in casting 4. During the downward movement of the plunger element 6^a, said plunger element engages with an arm 13 on a lever 14 pivoted to the casting 4, causing said arm to enter a slot G and another arm 16 on the lever 14 to become released from contact with the lower end of the plunger 6^a. The rotation of the lever 14 in this way brings about the retraction or rearward movement of a feeding pawl 18, which is pivoted to the lever 14, and the forward end of which is pointed to engage with the strip of staples 10. It will be understood that this pawl 18 is U-shaped in cross-section, so that the front pointed end of the pawl has two points which engage with the strip of staples, one point contacting on each side of the center thereof. Furthermore, the shape of this pawl 18 provides for conveniently attaching one end 19 of resilient means, such as a spring 19^a, which may be attached, as at 19^b, to the lever 14, in such manner as to depress the tip of the pawl into effective contact with the strip of staples 10 to be fed, incidentally to the rise of the plunger elements and the restoration of the parts to the position shown in Fig. 1.

The back-stop lever 23, which serves as a releasable means for holding the staple strip in the position to which it may be advanced by the means just described, is preferably engaged and depressed by means such as spring 20, which may be located around a pin 21 passing through the casting 4. The other end 22 of the spring 20 preferably engages with a recess in the top of back-stop lever 23, which may be carried by a pivot 24 in the casting 4. The lever 23 is also shown as U-shaped in cross-section, and its forward end preferably fits within the interior of the

feeding pawl 18. As shown, the forward end of lever 23 has two pairs of teeth 25 and 26 which engage with the staple strip introduced into the machine, while the rear end thereof forms a handle 27, which, when pressed, will release the feeding mechanism by elevating the feeding pawl 18 simultaneously with the elevation of the teeth 25 and 26, which are connected to said lever 23.

The described construction of the plunger 6, 6^a, forming two parallel plates differing in length in the manner indicated in Fig. 2, makes it possible for most of the associated parts to be made from sheet material, assembled at moderate expense, and effectively secured together in a form that is rigid, reliable and attractive,—the element 6^a being preferably provided in advance with a slot G, into which enters the point 13 and which may be made to terminate at the point I, just above the arm 16 of lever 14. In the organization shown and described, the need of any feather upon the plunger is obviated, as is also the need for any corresponding grooves within the casting 4.

The opening 28, Fig. 1, may be one of a plurality of lateral openings, which may be symmetrically arranged or, as shown, may be staggered to permit access to different regions from opposite sides, and to permit any desired inspection or adjustment.

The providing of the mentioned exterior recess 5^a in the top of the main casting 4 insures a proper seating and protection of the spring 18, obviating any sliding thereof; and it also renders the machine more compact, tending thereby to render it less liable to be accidentally overturned, either in use or otherwise.

By reference to Fig. 3, it will be noted that, in this embodiment of my invention the vertical inspection of clean-out slot 28 is preferably restricted to a transverse diameter substantially less than that of the bar 3, which, in turn, is preferably less than that of the plunger element 6. The transverse diameter of the plunger element 6, is, moreover, preferably less than the sum of the diameters of the bar 3 and the plates 3, 3^a. By the indicated simple and novel restriction in the diameter of the slot 28, and the correlation of the other diameters in the manner indicated, the strength of the lower portion of the casting in that region where the act of stapling puts a considerable lateral or expanding strain upon it, is retained substantially unimpaired,—although each aperture provided is entirely adequate to a machine in which liability to derangement is minimized by the expedients above mentioned.

One important innovation already referred to and tending to the mentioned minimizing of liability to derangement is best illustrated in Fig. 3, wherein the spacing

plates 3^a are shown to be of such width or thickness, and so placed, that, in the region where they approach or contact with the moving plunger element 6, the minute but 5 inevitable crevices between the associated parts 3, 3^a, and 4 are not in alignment with, but are staggered relatively to, those faces of the plunger which are parallel therewith. By this means any liability on the part of 10 the points of a defective or distorted staple to become wedged in one of the mentioned crevices is practically eliminated, and this feature contributes materially to the efficiency and durability of the present construction.

In the operation of the described embodiment of my stapling machine, when it is desired to apply staples to fabrics or the like for fastening sheets of the same together, a 20 strip of staples 10 is introduced into the machine by pressing the handle 27 downwardly, and introducing the staples over the rear end of the bar 3 through the U-shaped recess 3^a until the staple strip engages with the teeth 25 and 26 of the back-stop 23. The sheets of fabric or other materials or articles are now inserted by raising the casting 4, and introducing the same between the plunger 8 and the abutment 12. The sheets, or 25 the like, are now fastened together by pressing upon the knob 7, so that the plunger 6 severs a staple from the staple strip 10, and then forces that staple through the fabric, or the like, and finally crimps its ends in 30 the recess provided in the top of the abutment 12.

The downward movement of the plunger 6^a causes the feeding pawl 18 to be moved rearwardly, while the strip is held in fixed 40 position by means of the teeth 25 and 26. Upon the upward movement of the plunger 6^a, the pawl 18 is moved forwardly, thus feeding the strip far enough to bring the next staple under the plunger 6. The 45 stapling together of the sheets, or the like, in this way may be continued as long as desired, it being necessary only to replenish the supply of staples and to repeat the depression of the plunger. If, for any reason, 50 the slots 11 or any other portions of the feeding passageways should become filled with bent staples, the parts of the staple strip contained in the slot 11 may be readily removed by pressing the plunger 6 downwardly and the parts of the staple strip carried within the recess 3^a may be released by 55 pressing the projecting handle 27, thereby allowing the parts of the staple strip to fall out of the machine upon tilting. In 60 this way, any necessity for sending the machine back to the factory when clogged is obviated, and loss of material due to inability to utilize short ends of staple strips is also obviated. Again, it will be understood that, as in the machine of my men-

tioned prior application, whenever a machine contains only one remaining staple of the staple strip and a fresh staple strip is inserted, the new staple strip will be engaged by the rear teeth 26, and thereafter 70 the machine will function normally. On the other hand, in the case of previous staple machines the newly inserted staple strip is likely either not to engage with the one pair of teeth usually present in the back-stop, or to force the one remaining staple from the previous strip out of the apparatus, so causing the loss of the staple. Prior machines of this general type have also been made unduly tall, unduly complicated, and 75 unduly liable to derangement in one or more of the several respects above referred to.

While I have described my invention above in detail, I wish it to be understood that many changes may be made therein 80 without departing from the spirit thereof.

It should, furthermore, be understood that one of the main advantages of the present construction, compared with such prior constructions as aim at some provision for the release of the staple strip, lies in the fact that, in my construction, one hand will suffice for both the holding of the entire machine and the depression of the projecting handle 27 of the back-stop lever 23, the other hand being thereby left free for the grasping or catching of the released staple strip, or for 90 any other desired use.

I claim:

1. In a stapling machine, the combination 100 with a main frame or casting, of a plunger adapted to move therethrough, a cutter bar secured in said casting substantially at right angles to said plunger and adapted to co-operate therewith, and spacing plates interposed between said cutter bar and said casting, the lateral faces of the plunger overlapping the juxtaposed edges of the cutter bar and spacing plates.

2. In a stapling machine, the combination 105 with a main frame or casting, of a plunger comprising two plates adapted to move therethrough, a knob surmounting said parallel plunger elements and a cutter bar co-operating with one of said plates.

3. In a stapling machine, the combination 110 with a main frame or casting, of a bipartite plunger adapted to move therethrough and comprised of two parallel elements which are secured together near the top thereof and which are adapted to interfit with an aperture in one element of a surmounting knob.

4. In a stapling machine which comprises 115 staple feeding means, two parallel plates, one of which plates is provided with a slot and engages with said staple feeding means, and both of said plates being surmounted by a knob comprising a plurality of elements through one of which both of said plunger 120

- elements extend for effective attachment thereto.
5. In a stapling machine, a main frame or casting provided at the top with an exterior recess suitable for the seating of a spring, a spring therein, a bipartite plunger passing through said spring and returnable thereby, a knob on said plunger, and means for securing the elements of said plunger to one another and to said knob.
6. In a stapling machine, a main casting, a cutter bar secured thereto by spacing plates and adapted to carry a strip of staples advancing therethrough, means for advancing said staples, a bipartite plunger, and means for operating said feeding means by contact of parts thereof with an element of said bipartite plunger.
7. In a stapling machine, a main casting, a cutter bar adapted to carry a strip of staples, means for advancing such a strip therethrough, a bipartite plunger moving substantially at right angles to said cutter bar, one element of said plunger being adapted to cooperate with said cutter bar to sever and to drive staples carried thereby and the other element of said plunger being

adapted to operate said means for advancing the strip of staples.

8. In a stapling machine, a main casting provided with an exterior recess for seating a spring in the top thereof and with an interior recess, a bipartite plunger whose upper part is held together within a surmounting knob, said plunger passing through said spring and through both of said recesses, a cutter bar so secured to said main casting by spacing plates as to permit of the feeding of staples therealong, means for feeding staples therealong and for holding staples thereon, said cutter bar and said spacing plates and said plunger being of such diameters that the joints between the mentioned parts shall be staggered relatively to one another, one element of said bipartite plunger being adapted to cooperate with said cutter bar in the severance of staples and the other element thereof being adapted to operate said staple feeding means.

In testimony that I claim the foregoing, I have hereunto set my hand this 9th day of September, 1920.

FRIDOLIN POLZER.
